US0D1020845S

(12) **United States Design Patent** (10) Patent No.: **US D1,020,845 S**
(45) Date of Patent: ** Apr. 2, 2024

(54) **EYEWEAR FRONT FRAME**

(71) Applicant: **PAIR EYEWEAR, INC.**, New York, NY (US)

(72) Inventors: **Nathan Kondamuri**, Brooklyn, NY (US); **Sophia Edelstein**, Brooklyn, NY (US)

(73) Assignee: **PAIR EYEWEAR, INC.**, New York, NY (US)

(**) Term: **15 Years**

(21) Appl. No.: **29/877,600**

(22) Filed: **Jun. 8, 2023**

(51) LOC (14) Cl. **16-06**

(52) U.S. Cl. USPC **D16/300**

(58) **Field of Classification Search**

(57) **CLAIM**

The ornamental design for an eyewear front frame, as shown and described.

DESCRIPTION

FIG. 1 is a front perspective view of an eyewear frame. FIG. 2 is a rear perspective view of the eyewear frame.

FIG. 3 is a front view of the eyewear frame.

FIG. 4 is a rear view of the eyewear frame.

FIG. 5 is a left side view of the eyewear frame.

FIG. 6 is a right-side view of the eyewear frame.

FIG. 7 is a top view of the eyewear frame; and,

FIG. 8 is a bottom view of the eyewear frame.

The broken lines in the drawings depict portions of the eyewear frame that form no part of the claimed design.

1 Claim, 6 Drawing Sheets
